DITCHING, GRADING, AND LEVEE BUILDER MACHINE

Filed Feb. 14, 1921 2 Sheets-Sheet 2

UNITED STATES PATENT OFFICE.

WILLIAM A. STEELE, OF OWENSBORO, KENTUCKY, ASSIGNOR TO OWENSBORO DITCHER & GRADER COMPANY, OF OWENSBORO, KENTUCKY, A CORPORATION OF KENTUCKY.

DITCHING, GRADING, AND LEVEE-BUILDER MACHINE.

Application filed February 14, 1921. Serial No. 444,788.

To all whom it may concern:

Be it known that I, WILLIAM A. STEELE, a resident of Owensboro, in the county of Daviess and State of Kentucky, a citizen 5 of the United States, have invented certain new and useful Improvements in Ditching, Grading, and Levee-Builder Machines, of which the following is a specification.

My invention relates to an improvement 10 in ditching, grading and levee builder machines.

In machines of this character heretofore in use it has been necessary when the dirt was thrown out of the ditch, to move it 15 again by taking the machine out of the ditch and driving along side the pile of dirt in order to throw it further across the road.

One of the objects of the present invention is to provide for moving the dirt to the 20 center of the road with one passage of the machine through the ditch and this is accomplished by the use of an extension removably fastened to the rear end of the mold-board or cutting blade of the machine.

Another feature of the present invention 25 is a one-piece foot-board made of wide angle iron and forming a bracing throughout the major portion of the length of the land side of the machine.

Still another feature of the present invention 30 is an adjustment on the front end of the land side and the blade for the purpose of raising and lowering the blade in order to adjust it to cut more or less dirt 35 in ditching or road grading.

Still another improvement resides in my 40 double end swivel clevis, adapted to be used in connection with the goose-neck pulling beam which avoids the necessity of removing the goose-neck from the hitch bar when the machine is reversed as the swivel clevis admits of the goose-neck being turned entirely around thereby saving time in reversing the machine.

In the accompanying drawings—

Figure 1 is a view in perspective looking from the front of the machine.

Figure 2 is a view in perspective looking from the rear.

Figure 3 is a cross section.

Figure 4 is a view of the extension and base removed.

Figure 5 is a view showing the inside of the land side and mold-board or cutting blade. 55

Figures 6 and 7 are details.

Fig. 8 is a detail view of the pivot connection between the land side and mold-board;

Fig. 9 is a similar view showing the manner of obtaining a vertical adjustment of the forward end of the mold-board relative to the land side. 60

A, represents the land side of the machine. This is provided with an angle iron foot-board 1, made in a single piece which is quite an advantage in setting up the machine. It is of suitable width and it is sufficiently long to extend throughout the major portion of the length of the land side to 70 which it is bolted thereby bracing it and making it rigid. This foot-board 1, is provided with holes 2, to receive the seat 3. 65

B, represents a mold-board or cutting blade. The mold-board and land side are 75 provided with brackets 3' and 4, at their forward ends riveted thereon and through which a bolt 5, extends for pivotally connecting the land side and mold-board or cutting blade together. As shown in Figs. 80 8 and 9, a collar 5' is adapted to be placed upon the bolt 5 either between the upper projecting ends of the brackets 3' and 4 for raising the forward end of the mold-board relative to the land side, or between the lower projecting ends of the brackets 3' and 4 for lowering the forward end of the mold-board relative to the land side. 85

An extension 6, may be made of wood or other material and is of sufficient length to 90 carry the dirt plowed out of the ditch to a point at or approximately at the center of the road. This extension 6, is preferably provided with a hook 7, at its forward end by which it is detachably secured to the loop 95 8, at the rear end of the mold-board or cutting blade B. An angle iron brace 9, is preferably secured to the inner side of the extension 6, and a brace 10, provided with a hook 11, is detachably held in one of the 100

holes 12, in the angle iron brace 9, and a similar hook 13, on the other end of the brace 10, is detachably secured in one of the holes 12, in the foot-board 1, on the land side.

The usual double brace 15, extends from some point near the rear of the mold board or cutting blade to the foot-board as shown in Figures 1 and 2.

10 A goose-neck 16, arches around the upper edge of the mold-board or cutting blade extending vertically in the line of draft and its rear end is bent into a horizontal position at approximately right-angles to the 15 adjacent vertical portion and is detachably secured to a jaw 17, on the rear of the mold-board or cutting blade preferably by means of one end of the detachable end rail 18.

The forward end of the goose neck is provided with a double end swivel clevis 19, the front end of which is attached to the hitch bar 20.

In this way I have provided a complete and greatly improved machine of the character described and one in which the various parts may be easily applied or detached as occasion may require, the various parts all being removable and detachable and the

entire machine being capable of being reversed or turned over in order to throw the dirt the other way with the least possible trouble and loss of time.

I claim—

1. A machine of the character described including a land side, a mold-board or cutting-blade, brackets secured to the forward ends of said parts, a bolt pivotally connecting these brackets, one bracket of greater length than the other, and means removable from the bolt and insertible between adjacent ends of the brackets for maintaining an adjusted position between the forward end of the land side and mold-board.

2. A machine of the character described, including a land side, a mold-board or cutting blade, brackets secured to the forward ends of said members, a bolt pivotally connecting these brackets, and a collar adapted to be placed upon the bolt between the projecting ends of the brackets for raising or lowering the blade to cause it to cut more or less dirt in ditching or road-grading.

In testimony whereof I hereunto affix my signature.

WILLIAM A. STEELE.
